Primary Examiner—Paula A. Greene

(57) CLAIM

The ornamental design for cabinet handles, as shown and described.

DESCRIPTION

FIG. 1 is a perspective view of a cabinet handle showing our new design;

FIG. 2 is a top plan view thereof, the bottom is a mirror image; and,

FIG. 3 is a front elevational view thereof.

The broken lines are included for the purpose of illustration and form no part of the claimed design.

1 Claim, 2 Drawing Sheets
